UNITED STATES PATENT OFFICE.

WILLIAM H. McCLELLAND, OF HUNTINGDON, PENNSYLVANIA, ASSIGNOR, BY MESNE
ASSIGNMENTS, TO ROY P. M. DAVIS, OF MOUNT UNION, PENNSYLVANIA.

ADJUSTABLE MOLD.

Application filed December 15, 1924. Serial No. 755,936.

To all whom it may concern:

Be it known that WILLIAM H. McCLELLAND, a citizen of the United States of America, residing at Huntingdon, in the 5 county of Huntingdon and State of Pennsylvania, has invented certain new and useful Improvements in Adjustable Molds, of which the following is a specification.

This invention relates to molds and more 10 particularly to adjustable molds for making brick.

In the manufacture of molded brick where a slicker is used, the upper edges of the mold wears away under the action of 15 the slicker until it has to be discarded due to the fact that the thickness of the brick mold therein must be under specified limits. As much as 95% of the original material from which the type of mold now accepted 20 as standard in the industry is made, must be discarded as scrap when the mold becomes worn.

It is the object of the present invention to provide a mold which will not only have 25 a much longer life but one which will also obviate any variation in the thickness of the brick due to wear of the mold. A further object of this invention is to reduce by half the amount of material to be discarded 30 when the mold has reached the limit of wear.

In the accompanying drawings forming part of this specification:

Figure 1 is a plan view of a mold made 35 in accordance with the invention;

Figure 2 is a longitudinal sectional view through Figure 1, taken on the line 2-2;

Figure 3 is an end view of the mold, partly in section and partly broken away, 40 showing the upper and lower sections of the mold as originally assembled before any wear has taken place;

Figure 4 is a view similar to Figure 3 but showing the two halves of the mold adjusted after use to compensate for wear; and

Figure 5 is an end view of an alternative form of mold showing the two halves thereof adjusted after use to compensate for 50 wear.

Referring more particularly to the drawings wherein like reference numerals designate corresponding parts throughout the several views, 1, denotes a two part skeleton

mold comprising upper and lower sections 55 2 and 3 respectively. These sections which are identical one with the other in size and construction, comprise side plates 4, end plates 5, partitions 6, and end braces 7. Any suitable fastening means such as screws 60 8, are employed to connect the end plates 5, partitions 6, and end braces 7, to the side plates 4, of the respective sections.

The upper and lower sections of the mold are held together by means of bolts 9, which 65 pass loosely through openings 10, in the side and end plates of the lower section, and threadedly engage in corresponding aligned threaded openings 11, formed in the side and end plates of the upper section of the mold. The enlarged heads 12, of the bolts 9, are preferably countersunk in the enlarged portions 13, of the bores or openings 10. These bolts 9, also serve as dowels to hold the two halves or sections of the mold 70 together. Adjustment of the mold sections to compensate for the wearing away of the upper edges of the upper section of the mold is effected in a manner hereinafter described by means of threaded bolts or dowels 14, 75 which are threaded into bores 15, formed in the end plates 5, and loosely engaged at their upper ends in corresponding aligned openings 16, in the end plates of the upper section.

When the mold is manufactured and first used, it is assembled as shown in Fig. 3 with the two halves in direct contact, the total thickness of the mold being according to requirements. As the upper side wears away 90 due to the action of the slicker, the original thickness of the mold is restored by loosening bolts 9, and advancing bolts 14, the required amount. This operation is repeated 95 preferably at short intervals until it is necessary to face off the worn surfaces of the upper section of the mold, after which the original thickness is again restored by adjusting bolts 9 and 14 as previously described.

When the limit of wear has been reached the upper section 2, of the mold is discarded and a new section added, still retaining the lower section 3, which has had practically no wear.

In Figure 5, I have shown an alternative method of adjusting the thickness of the mold, this being accomplished by means of

shims 18, held in place and compressed by bolts 9, the bolts 14, not being needed in this form of the invention.

It has been found in actual practice that the space 17, caused by the separation of the two halves of the mold has no harmful effect on the quality of the brick due to the fact that this space fills up with the material from which the brick is made. The shearing action caused by the ejection of the brick produces the same smoothness and texture on the surface of the brick as is the case with the standard mold heretofore used.

Having thus described my invention, what I claim as my invention is:

1. A two part skeleton mold comprising upper and lower sections, said sections each having side and end walls, and partitions, means for aligning the walls and partitions of one section with the walls and partitions of the other section, and means for adjusting said sections into spaced relation with respect to each other.

2. A two part skeleton mold comprising substantially similar upper and lower sections, and means for adjustably connecting said sections together.

3. A two part skeleton mold comprising upper and lower sections, said sections each having side and end walls, bolts loosely passing through the side and end walls of the lower section and screwing into the side and end walls of the upper section, for connecting said sections together with their walls in alignment, and bolts screwing through the end walls of the lower section and engaging the end walls of the upper section, for adjusting said upper section away from said lower section.

In testimony whereof I affix my signature in presence of two witnesses.

WILLIAM H. McCLELLAND.
